UNITED STATES PATENT OFFICE

143,143

DESIGN FOR A COMBINED HAND CONTROL VALVE MOUNTING AND INDICATOR

Harold R. Fitz Gerald, Rocky River, and George E. Kriker, Cleveland, Ohio, assignors to The Midland Steel Products Company, Cleveland, Ohio, a corporation of Ohio

Application August 9, 1944, Serial No. 114,801

Term of patent 14 years

(Cl. D14—6)

To all whom it may concern:

Be it known that we, Harold R. Fitz Gerald and George E. Kriker, citizens of the United States, residing at Rocky River and Cleveland respectively, in the county of Cuyahoga and State of Ohio, have invented a new, original, and ornamental Design for a Combined Hand Control Valve Mounting and Indicator, of which the following is a specification, reference being had to the accompanying drawing forming a part thereof.

Fig. 1 is a frontal elevation of a combined hand

control valve mounting and indicator embodying my new design;

Fig. 2 is a side elevation of the same; and

Fig. 3 is a rear elevational view of the same on a reduced scale with the hand lever shown broken away for convenience of illustration.

We claim:

The ornamental design for a combined hand control valve mounting and indicator, substantially as shown.

HAROLD R. FITZ GERALD.
GEORGE E. KRIKER.
